UNITED STATES PATENT OFFICE

JOHN HENRY WYNDHAM, OF LEICESTER, ENGLAND, ASSIGNOR TO DALE FORTY AND COMPANY, LIMITED, OF BIRMINGHAM, ENGLAND

WHEEL SKATE OR THE LIKE

Application filed March 9, 1928, Serial No. 260,520, and in Great Britain March 18, 1927.

This invention relates to wheel skates and has for its object to provide a simplified and improved form of foot vehicle commonly known as a road skate.

5 In its broadest aspect the present invention consists in the provision of a three-wheel road skate or the like wherein the wheel base or foot supporting frame is adapted to be adjustable in such a manner 10 as to accommodate different foot dimensions, and according to a further feature of the invention means associated with movable elements of the foot supporting frame are provided whereby the toe portion of the 15 foot is readily engaged and securely maintained when the skate is in adjusted position. A still further feature of the invention is constituted by the fact that the foot supporting member is adapted to extend 20 rearwardly to a distance beyond the rear axle sufficient to enable the entire skate to be tilted about the rear wheels with the aid of the foot and thus temporarily lift the front wheel away from the surface of the 25 ground when it is desired to change the direction of movement of the skate. The wheel base is preferably located so that the centre of gravity of the skate is appreciably low with respect to the level of the ground, 30 thereby rendering the skate of enhanced stability.

Extensible or adjustable road skates have been proposed heretofore and according to one example of a two wheeled skate use has 35 been made of two longitudinally adjustable body members arranged so as to be underslung and intermediate the axles of respective end wheels, there being also provided toe engaging straps upon the forwardly located extension member and a heel embracing member mounted upon the rear extension member.

More particularly the present invention 45 comprises a three wheeled skate comprising two longitudinally adjustable wheeled plate members, toe and heel engaging means integrally associated respectively with each of said plate members and co-operating to secure the skate upon a foot in accordance 50 with the degree of adjustment made, said

heel engaging means being so located that the heel portion of the foot resides substantially in a region between the two rear wheels of the skate.

In order that the invention may be more 55 readily understood reference is directed to the accompanying drawings illustrative of one convenient form of road skate constructed in accordance with the invention, and wherein

Fig. 1 is a general side elevational view of the entire device.

Fig. 2 is a plan of that represented by Fig. 1, while

Fig. 3 is an underside plan view of the device illustrating more clearly the manner in which adjustment of the relatively movable parts is made.

Referring now to these drawings throughout the several views of which similar portions of the device are represented by like reference characters the numeral 2 designates a main platform or foot support made of steel metal or any other suitable material and of substantially rectangular form.

70 Co-operating with the said support 2 is provided an extension plate 3 arranged so as to be capable of sliding relatively to the support 2, and as may be observed from Fig. 3 the plate 3 has secured thereto by 75 rivets 4 a yoke member 5 terminating in a forked extension 6 at one end and an extending limb 7 adapted to slide over the underside of the support 2. The limb 7 is provided with an eyelet 8 through which the

shank of a bolt 9 may pass, said bolt being 80 adapted to extend from the plate 3 through a slot 10 provided in the plate 2 and in this manner the members 2 and 3 may be secured in adjusted position by means of a 85 clamping wing nut 11. In order to enhance the stability of the skate as a whole the

plates 2 and 3 are mounted relatively close to the ground and this is accomplished by providing an upturned portion of the forked 85 extension 6 so that a suitable front wheel 12 may be mounted at 13, a point substantially higher from the ground than the plane in which the plates 2 and 3 are located.

90 In a similar manner a relatively low 100

point of suspension may be attained for the rear wheel mounting of the device, and to this end the plate 2 is provided with a shaped member 14 riveted thereto at 15 and 5 provided with upturned bracket portions 15^a and 15^b to the upper ends of which are mounted suitable wheels 16^a and 16^b respectively.

The rear end of the plate 2 as may be seen 10 from Fig. 2 extends appreciably beyond the centres of the wheels 16^a and 16^b for the purpose of enabling the user to tilt the front wheel readily from the ground and alter its course.

15 The relative longitudinal adjustment of the plates 2 and 3 may be readily effected by merely slackening the wing nut 11 and sliding the said plates within the range afforded by the length of the slot 10 and 20 in order to prevent undue strain downwardly projecting guide stops 17 may be provided upon the plate 3, to limit the relative longitudinal adjustment of the plates 2 and 3. The device is illustrated in extended 25 form by A in Fig. 3 wherein the appropriate members are shown in dotted outline in such extended position.

In order to secure the skate to the foot of a user the plate 3 is provided with a curved 30 tongue or member 18 adapted to embrace a substantial portion of the toe cap, the heel of the wearer being adapted to reside within the curvature of a contact plate or member 19 provided upon the rear end of the plate 2. In this manner the skate may be secured to the foot without the aid of foot straps, it being merely necessary to adjust the plates 2 and 3 suitable for the size of the foot engaged and to tighten the wing nut 40 11 when in adjusted position. The curvature of the plate 19 adequately forms a guard whereby lateral displacement of the foot is limited to an extent sufficient to prevent undesired contact with the side wheels.

45 It has been found that a road skate embodied in the foregoing manner may be manufactured very inexpensively from stampings for most of the parts concerned and that the necessity for the provision of toe straps is entirely avoided, although of course, these may be employed as an additional means of support if desired. Furthermore owing to the fact that the rear axle is provided with suitable upwardly and outwardly cranked ends, wheels of a relatively 50 large diameter may be employed and the centre of gravity of the wheel base consequently brought to a considerably low position.

60 I claim:—

1. A three wheeled skate comprising two longitudinally adjustable wheeled sole and heel plate members, toe and heel engaging means integrally associated respectively 65 with each of said plate members and co-

operating to secure the skate upon a foot in accordance with the degree of adjustment made, said heel engaging means being so located that the heel portion of the foot resides substantially in the region between 70 the two rear wheels of the skate, said sole plate member being provided with a yoke having forwardly and rearwardly extending fork limbs, the former for the reception of the front wheel and the latter slideable on the underside of the heel plate member and provided with an eyelet, said heel plate member having a longitudinal slot, and a bolt in said slot and eyelet and detachably 75 clamping said sole and heel plate members together at any desired adjustment thereof.

2. A wheel skate as claimed in claim 1, in which the sole plate member has depending guide stops arranged to bear against opposite sides of the rearwardly extending 80 fork limbs.

3. A three wheeled skate, comprising two rear wheels and a single front wheel, two longitudinally adjustable foot supporting plate members carrying respectively toe and heel engaging means, means for supporting one of the plate members on its upper and lower surfaces, and means for locking the two plate members together in the adjusted 90 positions.

4. A three wheel skate, comprising two rear wheels and a single front wheel, two brackets for supporting the rear wheels, two longitudinally adjustable foot supporting plate members, toe and heel engaging elements mounted upon said plate members, said heel engaging element being connected and suspended below the two rear wheels to the supporting brackets, while the toe element is suspended below the front wheel. 100

In witness whereof I affix my signature.

JOHN HENRY WYNDHAM.
